4-POLYALKYLENEOXY-1-NAPHTHOLS

Milton Green, Newton Highlands, and Warren E. Solodar,
Watertown, Mass., assignors to Polaroid Corporation,
Cambridge, Mass., a corporation of Delaware
No Drawing. Filed Aug. 27, 1957, Ser. No. 680,618
7 Claims. (Cl. 260—613)

This invention relates to chemistry and more particularly to novel chemical compounds.

One object of this invention is to provide novel substituted naphthalene compounds and suitable synthesis for their preparation.

Another object of this invention is to provide novel substituted naphthalene compounds which are useful as dye intermediates.

Other objects of the invention will in part be obvious and will in part appear hereinafter.

The invention accordingly comprises the product possessing the features, properties and the relation of components which are exemplified in the following detailed disclosure, and the scope of the application of which will be indicated in the claims.

For a fuller understanding of the nature and objects of the invention, reference should be had to the following detailed description.

The novel compounds of this invention may be represented by the formulae:

(A)

and

(B)

wherein each R^1 is an alkylene group containing at least two carbon atoms and preferably a lower alkylene group containing no more than five carbon atoms, such as a propylene, ethylene, etc., group; n is 0 to 4; R^2 is an alkyl group and preferably an alkyl group containing no more than five carbon atoms such as butyl, propyl, ethyl, etc.; and R^3 is an alkyl group and preferably a lower alkyl containing no more than five carbon atoms, an aryl group or an aralkyl group such as a benzyl group.

In a preferred embodiment n is 0 to 2. Such compounds may be represented by the formulae:

(C)

and

(D)

2

The preferred compound of this invention is 4-(ethoxyethoxyethoxy)-1-naphthol of the structure:

As examples of other compounds within the scope of this invention, mention may be made of:

4-(butoxyethoxyethoxy)-1-naphthol

4-(ethoxyethoxy)-1-naphthol

and

4-(benzyloxyethoxy)-1-naphthol

The novel substituted naphthol compounds of this invention may be prepared by reacting a 1,4-dihydroxy-naphthalene with a suitable ether-substituted or polyether-substituted aliphatic alcohol in the presence of hydrochloric acid.

The novel substituted naphthylamine compounds may be prepared by reacting α -naphthol with a suitable ether-substituted or polyether-substituted aliphatic alcohol in the presence of hydrochloric acid, nitrating the resulting polyalkyleneoxynaphthalene compound, and reducing the resulting nitro-substituted compound to the amine.

As examples of ether-substituted aliphatic alcohols which have been used to prepare the novel compounds of this invention, mention may be made of:

Ethylene glycol monomethyl ether

60 Ethylene glycol monoethyl ether

Ethylene glycol monobutyl ether

65 1-butoxyethoxy-2-propanol

70 Diethylene glycol monomethyl ether

5

3. A compound as defined in claim 1, wherein R³ is a butyl group.
 4. As a compound, 4-(ethoxy-ethoxy)-1-naphthol.
 5. As a compound, 4-(ethoxy-ethoxy-ethoxy)-1-naphthol.
 6. As a compound, 4-(benzyloxyethoxy)-1-naphthol.
 7. As a compound, 4-(butoxy-ethoxy-ethoxy)-1-naphthol.
